UNITED STATES PATENT OFFICE

AUGUST C. ORTHMANN, OF MILWAUKEE, WISCONSIN, ASSIGNOR TO CHARLES P. VOGEL,
OF MILWAUKEE, WISCONSIN

LEATHER AND METHOD OF MAKING THE SAME

No Drawing.

Application filed September 19, 1928. Serial No. 307,056.

The invention relates to leather and the method of making the same.

Waterproof leather is a very desirable product for various uses, for example, shoe soles and belting. Heretofore, while waterproof leather could be produced, the same was not a desirable, saleable commodity inasmuch as the waterproofing mixtures or compounds invariably discolored the product and 10 interfered with the production of a satisfactory finished surface to one side of the product.

Chrome leather has been known to be a very desirable product for use as sole leather but where such leather has been waterproofed, as by stuffing with grease, rubber or various compounds to prevent water from penetrating the leather, in every instance the resulting color on the outer surface, generally the grain surface, was undesirable. Efforts were made to improve the chrome leather by the application of a vegetable tan on the surface but the product was not waterproof and waterproofing discolored it. Such 20 leather could be made waterproof to some extent but if made thoroughly waterproof the compounds used for this purpose invariably discolored the leather.

The object of the present invention is to 30 provide a process for treating leather, vegetable tanned, chrome tanned or chrome re-tanned with a vegetable tan, so as to render said leather waterproof and at the same time produce a finished colored surface on one side 35 thereof, preferably the grain side, which will not be discolored by the waterproofing compounds. This result has been obtained according to the present invention by coating one side of the tanned leather with coloring 40 matter mixed with a suitable vehicle to provide a substantially impervious coating. Thereafter the leather so treated is subjected to the usual process or method of waterproofing, such as by dipping the same in a hot, 45 waterproofing solution which penetrates the pores of the leather from the uncoated side to the coated side but does not show through said coated or colored side, whereby a waterproof leather is obtained having all the commercial advantages of ordinary leather. Any

suitable waterproofing solution known to this art may be used, such for instance as that disclosed in Patent No. 166,748.

The ingredients are as usual well mixed by heating and the leather dipped into this 55 hot mixture for a period to obtain proper penetration thereof and then removed. After dipping the coated side may be freed of the waterproofing compound in any suitable manner if such removal is necessary or desirable.

The coating above referred to consists of any suitable coloring matter, such as ground pigment or aniline dyes, mixed in a suitable vehicle, such as varnish, lacquer or pyroxyline, the lacquer generally being a compound containing pyroxyline. This coating is applied to the leather, generally to the grain side thereof, and when dry the leather is subjected to the usual waterproofing process 70 which, as previously noted, is generally a dipping operation into a hot, waterproofing compound. The vehicles above named for carrying the coloring matter do not detract from the flexibility of the leather and are 75 impervious to the waterproofing compound.

The result of the above described process is a new product since the finished leather is fully waterproof, the finished side of which is not discolored by the waterproofing process.

The pigments or coloring matter may be of any desirable color to give a desired effect.

What I claim as my invention is:

1. The process of producing waterproof leather which consists in applying an impervious, colored coating to one side of the leather and then dipping the leather so prepared into waterproofing compound in a heated condition.

2. The method of producing a finished waterproof leather which comprises fixing a color on one face thereof and subsequently impregnating the leather with a waterproofing compound incapable of modifying the color.

3. The method of producing a finished waterproof leather which consists in coating one side of the leather with a color carrying vehicle which is impervious to a waterproof-

ing material, dipping the leather so prepared into a heated waterproofing compound to impregnate the leather from the uncoated side, said waterproofing compound being incapable of penetrating the color carrying coating and being ineffective to modify the color.

4. The process of producing finished waterproof leather which comprises coating one side of a tanned leather with a coloring matter mixed in a carrying vehicle to form an impervious coating of the desired color and then impregnating the leather so treated with a waterproofing compound that penetrates the leather from the unfinished side.

5. As a new article of manufacture tanned waterproof leather as produced by the process of claim 2 having on one side an impervious color coating, said coating being unmodified by the waterproofing agent.

In testimony whereof, I affix my signature.
AUGUST C. ORTHMANN.
